UNITED STATES PATENT OFFICE.

SIDNEY RUHLAND, OF NEW YORK, N. Y.

BILLIARD-CUE BRIDGE.

SPECIFICATION forming part of Letters Patent No. 690,617, dated January 7, 1902.

Application filed October 25, 1901. Serial No. 79,915. (No model.)

To all whom it may concern:

Be it known that I, SIDNEY RUHLAND, a citizen of the United States, and a resident of New York city, county and State of New York, have invented certain new and useful 5 Improvements in Billiard - Cue Bridges, of which the following is a specification.

This invention relates to a cue-bridge for billiard and pool which will straddle and thus 10 clear any intervening object-ball and which will permit the play - ball to be properly sighted.

In the accompanying drawings, Figure 1 is 15 a perspective view of my improved cue-bridge; Fig. 2 a front view, and Fig. 3 a side view, thereof.

The letter *a* represents the forked support of the cue-bridge, composed of a pair of round- 20 ed diverging shanks adapted to straddle an object-ball *A*. The lower ends of the shanks are incased in rubber tips *a'*, so as not to injure the cloth. From the center of the fork *a* rises a perforated arm *b*, from one face of 25 which project rearwardly a series of tubular cue-guides *c*. Between these guides the arm

b is provided with wide sight-openings *b'*. A socket *b²* on arm *b* is adapted to receive a handle *d*.

The bridge is used in the usual manner and will clear any object-ball *A* intervening be- 30 tween the player and the cue-ball.

The cue *B* is introduced through that one of the tubular guides *c* which has the elevation desired, while the cue-ball *D* is sighted through the opening *b'* immediately above 35 such guide.

What I claim is—

A cue-bridge composed of a forked support adapted to straddle a billiard-ball, an arm projecting upwardly from said support, a se- 40 ries of tubular cue-guides projecting from the arm, and sight-openings between said guides, substantially as specified.

Signed by me at New York city, county and State of New York, this 24th day of October, 45 1901.

SIDNEY RUHLAND.
